UNITED STATES PATENT OFFICE.

HENRY C. MILLER AND JULIUS BAUER, OF MILWAUKEE, WISCONSIN.

TEMPORARY BINDER.

SPECIFICATION forming part of Letters Patent No. 587,986, dated August 10, 1897.

Application filed April 26, 1897. Serial No. 633,845. (No model.)

To all whom it may concern:

Be it known that we, HENRY C. MILLER and JULIUS BAUER, of Milwaukee, in the county of Milwaukee and State of Wisconsin, have 5 invented a new and useful Improvement in Temporary Binders, of which the following is a description, reference being had to the accompanying drawings, which are a part of this specification.

10 Our invention has relation to improvements in temporary binders.

The invention relates more particularly to that class of binders in which leaves are placed and secured between the side pieces constituting the cover of a book and firmly locked 15 therebetween and when unlocked any one or more of the leaves may be removed and others substituted therefor.

10 The invention will be found of especial utility when the leaves are so arranged as to constitute what is commercially known and designated as a "perpetual ledger."

15 The primary object of our invention is to provide an improved construction whereby the leaves can be readily inserted or extracted from any part of the book and when inserted by means of a simple manipulation can be securely held in place.

With the above primary object and other 20 incidental objects in view the invention consists of the devices and parts or their equivalents, as hereinafter more fully set forth.

In the accompanying drawings, Figure 1 is a perspective view showing a complete binder 25 embodying our invention. Fig. 2 is a longitudinal sectional view of Fig. 1 with parts broken away. Fig. 3 is a section on the line 3 3 of Fig. 2. Fig. 4 is a horizontal section on the line 4 4 of Fig. 3, and Fig. 5 is a detail 30 view of the locking-key.

Referring to the drawings, the numeral 6 indicates the under side piece and 7 the upper side piece constituting the cover. The rear binding-piece 8 of the under side 6 is 40 provided with the upwardly-extending back piece 9. The rear binding-piece 8 is also provided with vertical openings 10, with which a horizontal recess 11 communicates. There are preferably two of the openings 10, and 45 adapted to be passed therethrough are tubular posts 12. These posts are provided at their

lower ends with outwardly-extending annular flanges which extend into the outer enlarged portions of the horizontal recesses 11, said flanges forming therebetween annular recesses 13. A metallic strip 14 is disposed within the recesses 11 of the binding-piece 8, and this metallic strip 14 is provided with openings 15, which register with the openings 10 of the binding-piece 8, and the bordering 50 edges of these openings 15 extend into the annular recesses 13, formed by the flanges at the lower ends of the tubular posts. The tubular posts 12 are rectangular in cross-section with their greatest length longitudinally 55 of the ledger.

The rear binding-piece 16 of the upper side 7 of the cover is likewise provided throughout its length with a horizontal recess 17, with which vertical recesses 18, extending up from 70 the under side of said binding-piece, communicate. The upper ends of rectangular bars 19 are adapted to extend into the vertical recesses 18, each of said bars provided with parallel horizontal annular end flanges, which 75 have a space therebetween to form an annular recess 20, said annular flanges extending into enlarged portions of the horizontal recess 17. A metallic strip 21 is disposed within the horizontal recess 17 and extends the length 80 of the binding-piece 16. This strip is provided with openings 22, which register with the vertical recesses 18. The bordering edges of these openings extend between the annular flanges of the rectangular bars 19 into the 85 annular recesses 20, formed by said flanges. It will be understood that the bars 19 are of exactly the same shape as the tubular posts 12, but are smaller in cross-section than said posts and are so positioned as to extend down 90 to and telescope into said posts.

The rear binding-piece 8 is provided at opposite ends with the upwardly-extending plates 23. Upon their inner sides these plates are formed with recesses 24, which are adapted 95 to receive and form guideways for arms 25 25, depending from the under side of the upper binding-piece 16. These plates 23 and the arms 25 fitting therein not only assist in keeping the two side pieces of the cover in proper 100 relative position with respect to each other, but also prevent edgewise displacement of

the leaves between said side pieces of the cover.

Arranged adjacent to the inner side of the back piece 9 and coextensive in length therewith, but of less vertical height than said back piece, is a block 26. It will also be noticed that the upwardly-extending plates 23 at the ends of the binding-piece 8, as well as the tubular posts 12, do not extend upwardly flush with the upper edge of the back piece, but the upper ends of said pieces and posts are flush with the upper edge of the block 26. As the inner edge of the rear binding-piece 16 is coincident with the inner side of the back piece 9, it is evident that this arrangement of the tubular posts, plates 23, and block 26 permit the upper side piece and its binding-strip to be adjusted downwardly below the upper edge of the back piece as the leaves are removed, the adjustment downwardly being limited by the upper ends of the posts, end plates, and block. Ordinarily there will be sufficient leaves between the side pieces of the cover to bring the binding-strip of the upper side piece flush with the upper edge of the back piece.

The block 26 at a medial point is cut in or recessed, as indicated at 27. Into the space formed by this recess is fitted a casing 28. Within this casing is disposed a longitudinally-movable locking-bar 29, which at one end is provided with a series of teeth. The lower edge of this bar is provided medially with a recess 30, and said lower edge is supported upon ledges or flanges 31 31'. The upper edge of the bar is provided with an upwardly-extending lug 32. Between the bar and the face of the recess of block 26 is disposed a pivoted dog 33. The upper edge of this dog extends slightly above the corresponding edge of the longitudinally-movable bar and is provided with a forwardly-extending lug 34, which is adjacent to the upwardly-extending lug 32 of the bar. The free end of the dog is normally held down by means of a spring 35, pressing upon the upper edge of said dog. Secured to and extending down from the rear binding-piece 16 is a toothed plate 36, the teeth being arranged on the edge thereof adjacent to the toothed end of the longitudinally-moving bar. This plate is also provided with a vertically-elongated slot 37, into which a pin 38, extending from the block 26, passes. The back piece 9 of the cover is provided with a keyhole 39, which hole extends through the block 26, so that a key inserted through the keyhole will enter the casing 28 of the locking mechanism in position to operate said locking mechanism.

The peripheral edges of the upper annular flanges at the lower ends of the tubular posts 12 are cut away for a limited distance to form the shoulders 40 40. Adjacent to these cut-away portions are lugs 41 41, which when the tubular posts are turned are adapted to contact with either of the shoulders 40 in order to limit the extent of the turning of said posts.

The shoulders 40 are such distance apart as will permit a quarter-turn to be given to the annular flanges.

The leaves 42, which are inserted between the side pieces of the cover, are as usual provided with a hinge 43, of linen or muslin, pasted to the rear edge of the leaf and having a rectangular reinforcing-strip 44 on the rear edge of the hinge. This rectangular reinforcing-strip is provided with the openings 45 45, from which lead straight openings or slots 46 46, extending to the rear edge of said reinforcing-strip. The openings 45 are so positioned on the reinforcing-strip as when the leaves are inserted in place between the side pieces of the cover that said openings will register with the upwardly-extending tubular posts 12.

It will be understood that any desirable form of mechanism may be employed for locking the sides of the cover, although that herein shown and described will perhaps be found best adapted for the purpose. In order to lock the side pieces of the cover, all that is necessary to do is to insert a key, such as 47, through the keyhole 39. This key is then turned so that the ward 48 thereof will extend up in the recess 30 of the longitudinally-moving bar and act against the lower edge of the pivoted dog. With the continued turning of the key the said pivoted dog is turned on its pivot against the downward pressure of the spring until the forwardly-extending lug 34 of said dog is raised above the upwardly-extending lug 32 of the bar. This permits said bar to be moved longitudinally the required distance to cause the teeth thereof to engage with the teeth of the plate 36, and after the key has been turned so that the ward thereof is again out of the recess of the longitudinally-moving bar the dog is free to again turn downwardly on its pivot, and the forwardly-extending lug of said dog is then adjacent to the opposite side of the upwardly-extending lug of the movable bar, so that said bar is locked in firm engagement with the toothed plate. It is obvious that in order to unlock the side pieces of the cover, so that the upper side piece can be raised or lowered, all that is necessary is to insert the key and turn the same in the opposite direction. This will have the effect of again raising the dog, so as to bring its lug out of engagement with the lug of the bar and permit the movement of the bar in the opposite direction to disengage its teeth from the teeth of the plate 36, as clearly shown in Fig. 2.

To remove or insert a leaf all that is necessary is to unlock the binder in the manner pointed out. The squared end 49 of the key 48 is then inserted in one of the vertical openings 10 of the rear binding-piece 8 to engage the lower end of the tubular post. By turning this tubular post to the extent it is adapted to be turned—viz., one-quarter of a turn—the greatest width of the tubular post, which in Fig. 4 is shown transverse of the openings

45 of the leaves, is brought to a position at right angles to the position shown in said figure—that is, so that its greatest width will be in line with the straight slot 46 of the 5 leaves. The other tubular post is then adjusted in like manner. It will be obvious that either additional leaves may be now readily inserted in place or leaves removed from between the side pieces of the binder, and 10 when it is again desired to secure the leaves in place all that is necessary is to turn the tubular posts back to the position illustrated in Fig. 4, which effectually prevents the leaves from being withdrawn, as the greatest 15 widths of the tubular posts are now transverse to the straight slots 46, and said greatest widths of the tubular posts are greater than the widths of said straight slots.

What we claim as our invention is—

20 1. In a temporary binder, the combination, of upper and lower side pieces, revolvably telescoping parts extending respectively from the upper and lower side pieces, and adapted to move one within the other, as the side pieces 25 are brought closer together or farther apart, and leaves having openings near their rear edges, with narrower slots extending from said openings to the rear edges, the telescoping parts adapted to be locked against withdrawal out of the openings of the leaves, when 30 said telescoping parts are turned in one direction, and to be capable of withdrawal from the narrower slots of the leaves, when turned in the opposite direction.

35 2. In a temporary binder, the combination, of upper and lower side pieces, telescoping parts extending respectively from the upper and lower side pieces, and adapted to move one within the other, and to be given a partial revolution in either direction, and leaves having openings near their rear edges, with narrower slots extending from said openings to the rear edges, the telescoping parts adapted to be locked against withdrawal from the 45 openings of the leaves, when said telescoping parts are turned in one direction, and to be capable of withdrawal through the narrow slots of the leaves, when turned in the opposite direction.

50 3. In a temporary binder, the combination, of upper and lower side pieces, one of said pieces provided near its rear edge with a vertical opening intersecting a horizontal recess, a tubular post provided at or near one end 55 with an annular recess, a longitudinal strip fitting in the horizontal recess of one of the side pieces and provided with an opening registering with the opening of said side piece, the bordering edge of said opening of the 60 strip fitting in the annular recess of the post, a vertical bar fitting in a vertical recess of the other side piece of the cover, the other end of said bar adapted to telescope into the tubular post, a longitudinal strip fitting in a 65 horizontal recess with which the vertical recess communicates, said strip provided with an opening registering with said vertical re-

cess, the bordering edge of the opening of the strip fitting the annular recess of the bar, and leaves provided near their rear edges 70 with openings, and with narrower slots leading from the openings to the rear edges of the leaves, said openings adapted to register with the telescoping tubular post and bar, said telescoping parts adapted to be locked against 75 withdrawal from the openings of the leaves, when said telescoping parts are turned in one direction, and to be capable of withdrawal from the narrower slots of the leaves, when turned in the opposite direction. 80

4. In a temporary binder, the combination, of upper and lower side pieces one of said side pieces provided at its rear edge with a vertical opening, intersecting a horizontal recess, a tubular post provided at or near one 85 end with flanges forming a recess therebetween, a longitudinal strip fitting in the horizontal recess and provided with an opening registering with the opening of the side piece, the bordering edge of said opening of the 90 strip fitting in the recess formed between the flanges of the tubular post, a vertical bar rectangular in cross-section, and fitting at one end in a vertical recess in the other side piece of the cover, and provided with flanges having a space therebetween to form a recess, and said bar having its opposite end telescoping into the tubular post, a longitudinal strip fitting in the horizontal recess with which the vertical recess communicates, said strip 100 provided with an opening registering with said vertical recess, the bordering edge of said opening fitting the recess formed between the flanges of the bar, a lug projecting from one of the longitudinal strips, and adapted to 105 act against shoulders formed upon one of the flanges of a post or bar, when said post and bar are turned together in either direction, and leaves each provided near its rear edge with an opening and with a narrower slot extending from said opening to the rear edge of 110 the leaf, said opening adapted to register with the telescoping bar and tube, said telescoping parts adapted to be locked against withdrawal from the openings of the leaves, when 115 said telescoping parts are turned in one direction, and to be capable of withdrawal from the narrow slots of the leaves, when turned in the opposite direction.

5. The combination, of parallel longitudinal strips provided with a registering opening or openings, a tubular post or posts extending into the opening or openings of one of the strips, and provided on each side of said strip with flanges, and a bar or bars extending into the opening or openings of the other longitudinal strip, and provided on opposite sides of said strip with flanges, said bar or bars telescoping into the tube or tubes, and the two parts adapted to be revolved together. 120 125 130

6. The combination, of parallel longitudinal strips, a tubular post or posts, and a bar or bars telescoping into the post or posts, said

telescoping parts being revoluble in the parallel longitudinal strips.

7. In a temporary binder, the combination, of side pieces constituting the cover of the binder, a plate extending from one of the side pieces and provided with a toothed edge, a bar having teeth at one end, and at its upper edge provided with a projecting lug and a pivoted dog also provided with a projecting lug adapted to engage on either side of the lug of the bar to normally prevent longitudinal movement of the bar, said dog adapted to be raised by a key, or analogous device, so as to raise the lug of the dog out of engagement with the lug of the bar, whereby said bar

may be moved in either direction, its movement in one direction causing its teeth to engage the teeth of the plate, and its movement in the opposite direction causing its teeth to be disengaged from the teeth of the plate, the final withdrawal of the key permitting the dog to resume its normal position.

In testimony whereof we affix our signatures in presence of two witnesses.
